E. W. DECKER & M. A. MYERS,
UNDERGARMENT,
APPLICATION FILED DEC. 30, 1916.

1,229,905.

Patented June 12, 1917.

Ellen W. Decker and Marcus A. Myers,
By their Attorney

Philip Abbott.

UNITED STATES PATENT OFFICE.

ELLEN W. DECKER AND MARCUS A. MYERS, OF NEW YORK, N. Y., ASSIGNORS TO JULIUS KAYSER & CO., OF NEW YORK, N. Y., A CORPORATION OF NEW YORK.

UNDERGARMENT.

1,229,905.

Specification of Letters Patent. Patented June 12, 1917.

Application filed December 30, 1916. Serial No. 139,864.

To all whom it may concern:

Be it known that we, ELLEN W. DECKER and MARCUS A. MYERS, both citizens of the United States, and residents, respectively, of the borough and county of Richmond and borough of Manhattan, and county of New York, both in the city and State of New York; have invented a new and Improved Undergarment, of which the following is a specification.

Garments of the same general class as those contemplated by our invention have been long known and have been made of various materials, but have been objectionable for various reasons which need not be specified. It is the object of our invention to provide an undergarment of the class stated made from warp knitted fabric which shall avoid the objections referred to and produce an article of high grade adapted to use by those who do not regard price so much as quality, fit and satisfaction in other respects.

Referring to the drawings, Figure 1 is an elevation of a blank for the front of the garment; Fig. 2 is an elevation of a blank for one half of the back; Fig. 3 is an elevation of a blank for one of the front flaps; Fig. 4 is an elevation of a blank for one of the rear reinforces; Fig. 5 is a view, in perspective, of the front of a complete garment embodying our invention; Fig. 6 is a view, in perspective, of the rear of a complete garment embodying our invention.

1, see Fig. 1, is the front of the garment cut from a piece of flat warp knitted fabric, preferably of silk made on a so-called Milanese machine, and having the outline or shape substantially as shown. 2 is the edge of the neck opening, 3, 3, the edges of the arm openings, 4 the side edge shaped to fit the contour of the body, 5, 5, the leg portions, 6 the side margins of a recess made by cutting out a portion of the front in substantially the shape shown.

7, see Fig. 2, is one half of the back of the garment cut from the same fabric as the front 1, 8 the edge of the neck opening, 9 the edge of the arm opening, 10, one of the side edges which being stitched to the edge 4 of the front forms one of the side seams 24, see Figs. 5 and 6. 11 is the leg portion of the back. The edge of the back 7, which is opposite the edge 10, is of the

general contour shown in Fig. 2, that is to say, it has an upper straight section 12, cut on a slightly oblique line relative to the straight line of the goods, and below that an outwardly curving part 13, and below that a slight indentation 14, and below that another straight section 15, somewhat more oblique than the section 12. The other half of the back is in all respects the same as that just described except that being for the other side of the back, the relative positions of the edges will be reversed. The two parts of the back are seamed together along the section 12 on the line 16, shown in Fig. 6.

17, see Fig. 3, is one of the flaps for the front, there being one flap for each half of the front. They are preferably made of the same material as the front and back and of the contour shown. The curved margins 18 of these flaps are stitched respectively to the margins 6 of the front forming the seam 25, as shown in Fig. 5. The upper margins 19 of the flaps are stitched to the right and left respectively of the front at the apex of the cut out portion thereof. For the sake of clearness in illustration but one flap is shown in Fig. 1. Both are shown in Fig. 5.

20, see Fig. 4, is the reinforce for one half of the back and it is applied thereto as shown in dotted lines in Fig. 2, its edge 21 paralleling the edge 15 and its side margins 22 being stitched to the back 7 and its recess 23 coinciding with the recess 14.

It will of course be understood that there will be a similar reinforce for the other half of the back and also that the flaps 17 will each be reinforced by having their thickness doubled throughout their entire area, as is usual in garments of this class. These various reinforces, while desirable, may be omitted.

The assembling of the garment is as follows:

As stated above, the edges 12 are stitched together to form a whole back, and the edges 10 of the back 7 are stitched to the edges 4 of the front 1 to form the side seams 24 shown in Figs. 5 and 6, the edges 18 of the flaps 17 are stitched to the right and left margins 6 respectively of the cut out portion of the front 1, it being understood that there will be four of these flaps, two superposed upon one another for each side of the front, to act as a reinforce. The margins

19 extend to the right and left respectively of the apex of the cut out portion of the front and are stitched to the front. The free edges of the flaps 17 overlap and afford 5 perfect closure for the front of the garment, and also perfect fit, resulting in extreme comfort for the wearer. The edges 15 of the back are stitched respectively to the edges 26 of the flaps to form the leg 10 seam 27.

The projecting curved portions 13 of the back overlap one another as shown in Fig. 6, and at their upper end are stitched respectively to opposite sides of the back for 15 a short distance and thus afford perfect closure for the rear of the garment and also perfect fit, resulting, as in the front, in extreme comfort for the wearer.

It will be obvious to those who are familiar with such matters that modifications may be made in the details of the construction above described and illustrated without departing from the essentials of the invention. We therefore do not limit ourselves 25 to the details shown and described.

We claim:

1. An undergarment cut to shape from flat warp knitted piece goods comprising a one piece front, a two piece back, front and rear openings, overlapping flaps added to the front at the front opening and which act as a closure therefor, and each piece of the back having a projecting part integral therewith which parts overlap and form a closure for the rear opening.

2. An undergarment cut to shape from

flat warp knitted piece goods comprising a one piece front, a two piece back, front and rear openings, overlapping flaps added to the front at the front opening and which act as a closure therefor and also form part of the leg portion, and each piece of the back having a projecting part integral therewith which parts overlap and form a closure for the rear opening.

45

3. An undergarment cut to shape from flat warp knitted piece goods comprising a one piece front, a two piece back, front and rear openings, each of the back pieces having a projecting part integral therewith extending to substantially the waist line of the garment which parts overlapping each other form the closure for the rear opening, and flaps added to the front at the front opening which overlapping act as a closure 55 therefor.

55

4. An undergarment cut to shape from flat warp knitted piece goods comprising a one piece front, a two piece back, front and rear openings, each of the back pieces having a projecting part integral therewith extending to substantially the waist line of the garment which parts overlapping each other form the closure for the rear opening, and flaps added to the front at the front 60 opening and forming part of the leg portion and which overlapping act as a closure for the front opening.
